UNITED STATES PATENT OFFICE.

PAUL I. ANDREWS, OF KENNEBUNK, MAINE.

CYLINDRICAL CAN.

1,166,168.

Specification of Letters Patent. Patented Dec. 28, 1915.

Application filed August 6, 1915. Serial No. 44,114.

To all whom it may concern:

Be it known that I, PAUL I. ANDREWS, a citizen of the United States, residing at Kennebunk, county of York, State of Maine, have invented a certain new and useful Improvement in Cylindrical Cans, of which the following is a specification, reference being had therein to the accompanying drawings.

10 The invention relates to cylindrical cans of fiber such for instance as roving cans. In cans of this character it is important to have the rim strengthened by some kind of reinforcement and it is also desirable that this reinforcement should not project into the interior of the can, but that the inner surface should be entirely smooth and free from inwardly projecting portions. The best form of reinforcement is to make the top 15 with an outward double roll integral with the body of the can. One form of such double roll is shown in Patent No. 1,100,516, granted to me June 16, 1914. I have found that when the can is made seamless and 20 with a double roll of that character the roll can be made perfectly but when it is attempted to form such a roll on the top of a riveted can in which the cylinder is made by rolling a sheet into a cylindrical form 25 having overlapping edges which are riveted together, the double thickness due to the overlapping portions causes an indentation or a wrinkle in the roll which is objectionable.

30 The object of the present invention is to cut or form one of the overlapping edges in such manner that when the roll is turned no wrinkle or indentation will be produced, but it will lie smooth, as do the other portions of the roll.

35 The invention will be fully understood by reference to the following description taken in connection with the accompanying drawings and the novel features thereof are 40 pointed out and clearly defined in the claim at the close of this specification.

45 In the drawings, Figure 1 is a perspective view of a riveted can having a roll embodying the invention. Fig. 2 is a sectional view 50 showing the roll. Fig. 3 is a side elevation enlarged of the cylinder partly broken away with the overlapping edges riveted together

before the roll is turned showing the notched edge embodying the invention. Fig. 4 is an enlarged side elevation partly 55 broken away after the top is turned to form the roll.

Referring now to the drawings, 1 represents the can or cylinder of fiber with overlapping edges 7, 8, secured together by 60 rivets 2. The outside overlapping edge 7 is formed with a notch 3 cut in some distance from the edge before the roll is turned. The cylinder is then put into a suitable press and the double roll 4 is then formed, and in so 65 forming the roll the edges 5, 6 of the notch 3 will be brought down close together as shown in Fig. 4, leaving simply a thin line or crevice which will be entirely concealed because in the process of producing the roll the 70 overlapping portion 7 which before the roll was formed was on the outside is rolled in and covered by the then overlapping portion 8 which before rolling was covered by the lap portion 7. If it were not for the notch 3, the 75 material between the edges 5, 6 of the notch and which was removed by forming the notch would have been bulged out, forming a wrinkle.

What I claim is:—

80 A can having a cylindrical body composed of a sheet of fiber rolled into a cylindrical form with overlapping edges riveted together and having an outwardly turned radial rim roll integral with said body and 85 extending entirely around the periphery of the rim including said overlapping portions, said roll having an outwardly turned curved upper portion, thence a downward turn, thence a turn toward the body, thence an 90 upward bend and thence another outward turn intermediate said upper and lower turns, the outer overlapping side having a cut out notch in that portion of its edge near the top which is on the outside edge 95 before the roll is formed and which is entirely inclosed within the roll after the roll is formed.

85 In testimony whereof I affix my signature, in presence of two witnesses.

PAUL I. ANDREWS.

Witnesses:

C. W. ANDREWS,
W. F. WATERHOUSE.
